UNITED STATES PATENT OFFICE.

GUSTAF A. H. WAHLIN, OF GARVIN, MINNESOTA.

COLLAPSIBLE REEL.

1,177,554.

Specification of Letters Patent. Patented Mar. 28, 1916.

Application filed March 19, 1915. Serial No. 15,602.

To all whom it may concern:

Be it known that I, GUSTAF A. H. WAHLIN, a citizen of the United States, residing at Garvin, in the county of Lyon and State 5 of Minnesota, have invented new and useful Improvements in Collapsible Reels, of which the following is a specification.

The present invention relates to improvements in binding reels for harvesting machines or the like.

It is the object of this invention to provide a reel of this character wherein the parts are capable of being collapsed when not in use, and possessing a novel construction of means for locking the parts in either operative or collapsed position.

Other objects will appear as the nature of the invention is better understood, the same residing in the combination, construction and arrangement of parts hereinafter more fully described.

In the drawing forming a part of this application like numerals of reference indicate similar parts in the several views 25 wherein:

Figure 1 is a front elevation. Fig. 2 is a longitudinal sectional view with the locking lever in operative position. Fig. 3 is a similar view showing the lever in inoperative position. Fig. 4 is a view showing the parts in folded position. Fig. 5 is a transverse sectional view. Fig. 6 is a detail view of one of the disks.

Referring to the drawing in detail 5 35 designates a hollow shaft upon which the reel is mounted.

The reel consists of what is termed spaced hubs 6 and 7 respectively, each hub comprising a plurality of apertured disks 8. 40 Each disk is provided with a radial extension 9 to which the spokes 10 are riveted or otherwise secured. By reason of this fact each hub consists of as many disks as there are spokes, the latter being bifurcated 45 at their upper ends for the reception of the blades 11 in the manner clearly shown. The disks of each hub are loosely mounted upon the shaft 5 and have independent rotary and sliding movements, to permit the blades 50 to be folded in superimposed relation when not in use. Each disk however is provided with an opening 12 and a lug 13, the lug of one disk being adapted to enter the opening 12 on the adjacent disk, when the blades

are equally spaced or in other words arranged in operative position.

Slidably mounted upon the shaft between the spokes and arranged adjacent the hub 6 is a sleeve 14, the latter being connected to the locking lever 15 by a pin 16 passed through the sleeve and side portions 17 of the lever. The pin 16 operates through a longitudinally disposed slot 18 in the shaft, to permit necessary reciprocatory movement of the sleeve 14 to lock the reel upon 60 the shaft, as well as to release the same to permit folding of the parts upon reverse movements of the lever in the manner presently described. The lever 15 is pivotally connected to the free ends of a U-shaped 70 yoke member 19, the latter having its cross piece 20 passed transversely through the shaft for swingingly supporting the yoke thereon. By reason of this construction it will be obvious that when the lever 15 is 75 swung down into engagement with the shaft 5, the sleeve 14 is forced against the innermost disk of the hub 6, thereby moving the entire series of disks into frictional engagement with each other, and effectively locking 80 the parts in operative position between the sleeve 14 and a fixed collar 21 on the shaft 5, and against which the outermost disk of the hub 6 is adapted to bear.

Mounted upon the shaft 5 beyond the outermost disk of the hub 7 is a collar 22 having a pin 23 passed therethrough and the shaft 5, and operating within the slot 24 in the shaft, to permit sliding movement of the collar thereon. A rod 25 is arranged within 90 the shaft and terminally connected to the pins 16 and 23 respectively, so that when the lever 15 is swung into engagement with the shaft 5, the collar 22 will be moved in the same direction as the sleeve 14 and simultaneously therewith, to bring the collar 22 into engagement with the outermost disk of the hub 7. The collar 22 forces the disks of the series into frictional engagement 95 with each other, thereby effectively locking the parts in operative position between the collar 22 and the collar 26 fixed on the shaft against which the innermost disk of the hub 7 is adapted to bear.

When the reel is not in use, the component parts of the latter may be readily and easily folded in the manner shown in Fig. 4, by simply raising the lever 15, thus simulta-

neously moving the sleeve 14 and collar 22 out of engagement with the disks of the respective hubs, thereby permitting each blade to be independently moved to any desired 5 adjusted or folded position.

Encircling the shaft 5 is a coil spring 27 having one end bearing against the innermost disk of the hub 6, and its opposite end bearing against the flange 28 of the sleeve 10 14. This spring operates to initially hold the spokes with the blades in operative or set position, until the locking lever 15 is operated to effectively lock these parts in fixed 15 relation. In addition to this function of the spring, the latter also exerts a pressure against the disks when the parts are folded to retain the parts in this position.

It will be observed that each blade is supported by two spokes, and that each spoke 20 has associated therewith one of the disks that constitute the hubs 6 and 7 respectively. The disks are so arranged that the innermost disk of the hub 6 is a companion to the outermost disk of the hub 7, as both of these 25 disks are associated with the spokes supporting the same blade, this order of arrangement being the same with regard to the other disks of both hub structures. Manifestly the spring 27 operates with the same 30 effect upon the disks of the hub 7 as those constituting the hub 6 and that the operations are simultaneous.

It is believed that from the foregoing description the nature and advantages of the 35 invention will be readily apparent to those skilled in the art to which the invention pertains, without requiring a more extended explanation and therefore the same has been omitted. However I desire to have it understood that I do not limit myself to the 40 precise construction and arrangement of parts herein shown and described, and that various changes may be made when desired as fall within the scope of the appended 45 claims.

What is claimed is:—

1. A collapsible reel comprising a plurality of relatively movable members, a shaft supporting said members, each member having spaced bearings slidably mounted upon the shaft, the adjacent bearings of each series being formed with coöperating means for interfitting engagement with each other, a spring encircling the shaft and bearing 50 against the innermost bearing of one series for temporarily holding said members fixed relatively in a predetermined position, and means for positively locking the members in said position.

60 2. A collapsible reel comprising a plurality of independent adjustable members, a shaft supporting said members, each member having spaced bearings slidably mount-

ed upon the shaft at remote points, the adjacent bearings of each series being formed 65 with coöperating means for interfitting engagement with each other on a predetermined position of said members, a spring encircling said shaft and bearing against the innermost bearing of one series for temporarily holding 70 said members in adjusted position, a sleeve slidably mounted on said shaft and adapted to engage said innermost bearing for positively locking the members in adjusted position, and an operating lever 75 associated with said sleeve.

3. A collapsible reel comprising a plurality of relatively movable members, a shaft supporting said members, each of said members having spaced bearings slidably mounted 80 upon the shaft, a spring encircling said shaft and engaging the innermost bearing of one series, the adjacent bearing of each series being formed with an opening and lug adapted to be moved under the action of said 85 spring into interlocking engagement upon a predetermined position of said members, and means for positively locking said members in adjusted position.

4. A collapsible reel comprising a plurality of independently adjustable members, a hollow shaft supporting said members, each of said members having spaced bearings 90 slidably mounted upon said shaft, a sleeve slidably mounted upon the shaft, a collar 95 slidably mounted upon said shaft, a rod connecting said sleeve and collar, and an operating lever connected with said sleeve for simultaneously moving the latter and said collar into effective engagement with the 100 bearings of each series for positively locking the same and said members fixed relatively in adjusted position.

5. A collapsible reel comprising a plurality of relatively movable members, a shaft 105 supporting said members, each member having spaced bearings slidably mounted upon the shaft at remote points, the adjacent bearings of each series being formed with an opening and a lug for interlocking engagement 110 with each other, means for simultaneously moving the respective members of each series into interlocking engagement with each other, including a sleeve slidably mounted upon the shaft and adapted to be 115 moved into engagement with the innermost bearing of one series, a connection between the sleeve and the bearings of the other series, and an operating lever associated with the sleeve.

In testimony whereof I affix my signature in presence of two witnesses.

GUSTAF A. H. WAHLIN.
